UNITED STATES PATENT OFFICE.

JOSEPH A. GROEBLI, OF NEW YORK, N. Y.

EMBROIDERING-MACHINE.

1,228,666.

Specification of Letters Patent. Patented June 5, 1917.

Application filed July 12, 1916. Serial No. 108,777.

To all whom it may concern:

Be it known that I, JOSEPH A. GROEBLI, a citizen of the United States, residing at No. 307 West Fourth street, city, county, and 5 State of New York, have invented certain new and useful Improvements in Embroidering-Machines, of which the following is a specification.

My invention relates to embroidering machines in which a tambour frame carries the fabric to be embroidered, moving it step by step into various stitch positions and requiring the periodical shifting of the fabric in the tambour frame and the returning of the 15 tambour frame to or toward an initial position. And my improvements are directed particularly to means for optionally bringing about these two operations of shifting the fabric and returning the tambour frame 20 to a greater or less extent simultaneously.

One system of means for accomplishing these results is shown in my Letters Patent No. 1,166,676 of January 4th, 1916, wherein the return of the tambour frame toward its 25 initial position is accomplished through so-called "automat" mechanism by which it is moved into its successive stitch positions. And my present invention is intended as an improvement on the mechanism of that 30 patent whereby the returning of the tambour frame may be brought about directly through the fabric shifting mechanism, to such an extent as the operator may wish, and simultaneously with the shifting of the 35 fabric and irrespective of the particular means that may be employed for moving the tambour frame into its successive stitch positions which may be accomplished in either of the well known manners, for instance, by 40 the employment of a pantograph apparatus, such as is illustrated in my Letters Patent No. 1,137,312 of April 27th, 1915.

In the drawings Figure 1 is a front view of one end of a tambour frame embodying 45 my invention; Fig. 2 is a back view of the same, the floor bracket and bar being omitted; Fig. 3 is an end view of the same looking to the right on Fig. 1; and Fig. 4 is a front elevation of the frame, tambour 50 frame and positioning mechanism of an em-

broidering machine, centrally shortened, and partially broken away for clearness.

In the tambour frame 2 are mounted two pairs of fabric rollers 3, 4 and 3, 4, the lower roller 4 of each pair being shown provided 55 with the worm gear 6 driven by a worm 8 on a vertical shaft 10 carrying a worm gear 12 meshing with a worm 14 on the shaft 15. These portions of my apparatus correspond with the parts which are similarly numbered 60 in my Patent No. 1,166,676; and I desire it to be understood that the upper fabric rollers 3, 3 may be driven from ends not shown in my present application by similar means, such as are shown in my aforesaid Letters 65 Patent. The bar 18 is provided with a threaded extension 19 passing up through a bracket 20 and through a hubbed worm gear 21 meshing with a worm 22 carried by the shaft 16, which is the shaft for applying the 70 vertical tension to the fabric. This bar 18 is provided with a pair of arms 23, 23 pierced to slide upon the shaft 10, and embracing the worm 8 so as to raise or lower the worm and shaft bodily when the shaft 75 19 is drawn up or down through the worm gear 21 as the latter is rotated by worm 22 upon shaft 16.

The construction of my apparatus thus far is in accordance with the mechanisms already illustrated by me in previous patents, this description having been given for the purpose of clearness in explaining the application of my improvements. And it may be here stated that the shafts 15, 16 and 17 80 represent shafts, common in machines of this class, whereby, respectively, the fabric is reeled, and the vertical tension and the horizontal tension are applied and released. The particular means by which these shafts 85 15, 16 and 17 are driven is not material to my present invention.

In the drawings I have shown each shaft as provided with a beveled gear adapted to mesh with a corresponding beveled gear 95 upon a driving shaft not shown.

In operation the upper fabric rollers 3, 3 turn in an anti-clockwise direction when looked at in the position shown in Fig. 3. The shaft of the upper roller of the lower 100

pair is provided with an extra gear 30 mounted at its end and traveling with it.

A guiding rod 31 is mounted in brackets 32 secured beneath the machine, as upon the 5 floor. A bar 33 has a hub 34 adapted to slide and rotate upon the rod 31 so that the bar 33 may be swung to and fro upon and also moved along the rod 31.

This rod 33 extends up between guide 10 fingers 35, 35 on the lower part of the tambour frame, and through an opening in an arm 36 of a lever 37 mounted upon a pivot 38 attached to the side of the tambour frame. Therefore the rod 33 will be moved 15 laterally with the tambour frame by the fingers 35 and may be swung toward or away from the tambour frame by the lever 37. Upon the bar 33 is mounted a toothed rack 39 by means of arms 40 and 41 through 20 which the bar 33 passes.

A set screw 42 may be employed to lock the rack 39 to the bar 33. And a collar 43 may be fastened upon the bar 33 to limit the downward shifting of the rack 39. The 25 bar 18 has a downward extension 44 with a laterally turned arm 45 extended beneath an arm 46 of the lever 37; and this arm 46 is normally drawn down by a tense spring 47, one end of which is attached to the arm 46 30 while the other end is attached to a lug on the tambour frame.

It will be seen, therefore, that when the lever 37 is swung in toward the tambour frame, the rack 39 may be brought into engagement with the gear 30; and when the movement of lever 37 is reversed the rack and gear may be separated.

The adjustment of the parts is such that when the vertical tensioning has been completed by the drawing upward of the bar 18, by the worm gear 21 threaded upon its upper end, the arm 45 will raise the arm 46, thereby rocking out the lever 37 so as to separate the rack 39 from the gear 30; while, 45 when the vertical tension has been released by the lowering of the bar 18, the arm 45 will permit the arm 46 to be drawn down sufficiently by the spring 47 so that the rack 39 may be brought into mesh with the 50 gear 30.

The tambour frame 2, may be mounted, counterbalanced and positioned in any well known manner. In Fig. 4 I have shown it as mounted in a frame 50, guide arms 51, 51 55 on the tambour frame passing through vertical slots in the uprights of the frame 50, the tops and bottoms of which slots are indicated by broken lines 52, 52. This permits the tambour frame to be raised and lowered, 60 its guide arms 51, 51 sliding in the slots. Rods 53, 53 are pivoted to the top of the tambour frame and to bell cranks 54, 54, connected by a bar 55. And one of the bell cranks 54 is provided with a counterbalance

weight 56. This mechanism serves to balance the tambour frame so that it may easily be moved vertically or laterally.

A pantograph apparatus 57, 58, 59, 60, is pivoted at one end, 61, to a lug of the frame 50, 50, and, at the pivotal point of the bars 70 58 and 59, to a rod 69 detachably held by a set screw 62 in a guide 63 fastened to the tambour frame 2.

At the end of the arm 60 is the pattern tracer 64. When this tracer is moved step 75 by step over the pattern 65, the pantograph mechanism will cause corresponding positioning movements to be made by the tambour frame. If desired the pantograph may be disconnected from the tambour frame, by 80 loosening the set screw 62, before the tambour frame is moved back to its normal, initial position.

It will be observed that the shaft 15 is carried across the top of the tambour frame 85 and connected through a second worm 14 with a worm gear 66, similar to the worm gear 12, on the end of shaft 67, which shaft, through worms, corresponding to worms 8, 8 on shaft 10, meshing with worm gears 68, 90 68 on rollers 3, 3, turn those rollers in synchronism with the rollers 4, 4.

This arrangement of the machine frame, balancing mechanism and pantograph apparatus is not new. But I have shown it to 95 assist those skilled in the art more readily to understand the application of my present invention than they might otherwise be able to do.

The use of an adjustable connection between the pantograph and the tambour frame has long been known in the art. And illustrations of such adjustable connections may be found, for instance, in the Swiss patent to Heinrich Spühl, No. 5693 of November 7, 1892, where both vertical and lateral adjustment is provided for, and in the Swiss patent to F. Saurer & Söhne, No. 2 of November 15, 1888.

In practice my apparatus may be operated as follows:—

During the normal operation of embroidery, the rack 39 will be thrown free of the gear 30, because the arm 46 is lifted by the arm 45; and the bar 33 will slide back and forth upon the rod 31 as the tambour frame moves to and fro; while the frame may freely move vertically in relation to the bar.

When it is desired to shift the fabric and readjust the tambour frame back toward its initial position, the bar 18 is slackened downward, thereby releasing the final vertical tension on the fabric just in advance of the forward reeling movement of the upper fabric rollers 3, 3. This downward movement of the bar 18 allows the lever 37 to be swung in by the spring 47, so as to throw the rack 39 into mesh with the gear 30. The fabric

rollers 3, 3 next revolve shifting the fabric forward; and simultaneously the gear 33 travels down along the rack 39 thereby drawing the tambour frame downward to the end of the rack, unless the movement is terminated by stopping the rotation of the fabric rollers or separating the rack and gear. When the gear has traveled to the end of the toothed part of the rack it may 10 continue to revolve against the plain surface below the rack, the adjustable arrangement of the rack on the bar 33 permitting its adjustment so that the lowering of the tambour frame may be stopped at any predetermined point. Furthermore, the operator may disconnect the rack and gear at any time by swinging out the lever 37, thereby also terminating the downward movement of the tambour frame. And, when the reeling 20 of the fabric has been completed and the final vertical tension applied, the raising of the bar 18 will cause the lever 37 to be swung out, thereby throwing and holding the rack 39 out of engagement with the gear 30 so 25 that the embroidering of the next pattern may be proceeded with.

It will be seen, therefore, that by means of my improvements the tambour frame may be automatically returned to a predetermined initial position while the fabric is being shifted, or such return movement may be prevented or limited by the manual control of the operator as circumstances may require, and that this may be done irrespective 30 of the means by which the tambour frame is moved step by step during the embroidering 35 operation.

Having thus described my invention, what I claim and desire to secure by Letters Patent of the United States is:—

1. The combination, in an embroidering machine, of a tambour frame provided with fabric carrying and shifting means, means for moving the tambour frame step by step 45 into stitch positions, and means independent of the tambour frame moving means for automatically returning the tambour frame toward an initial position.

2. The combination, in an embroidering machine, of a tambour frame provided with fabric carrying and shifting means, means for moving the tambour frame step by step into stitch positions, and means independent of the tambour frame moving means for 55 optionally automatically returning the tambour frame toward an initial position.

3. The combination, in an embroidering machine, of a tambour frame, fabric carrying and shifting means mounted therein, 60 and means actuated by such fabric carrying and shifting means for moving the tambour frame in a direction reverse to the shift of the fabric.

4. The combination, in an embroidering

machine, of a tambour frame, fabric carrying and shifting means mounted therein, and automatic means actuated by such fabric carrying and shifting means for moving the tambour frame in a direction reverse to the shift of the fabric. 65

5. The combination, in an embroidering machine, of a tambour frame, fabric carrying and shifting means mounted therein, and automatic and manually controllable means actuated by such fabric carrying and 75 shifting means for moving the tambour frame in a direction reverse to the shift of the fabric.

6. The combination, in an embroidering machine, of a tambour frame, fabric carrying 80 and shifting means mounted therein, and means actuated by such fabric carrying and shifting means for automatically moving the tambour frame a predetermined distance in a direction reverse to the shift 85 of the fabric.

7. The combination, in an embroidering machine, of a tambour frame, fabric carrying and shifting means mounted therein, tensioning means for causing the fabric 90 shifting means to apply tension to a fabric, and means automatically controlled by the tensioning means and actuated by the fabric carrying and shifting means for moving the tambour frame in a direction reverse to the shift of the fabric. 95

8. The combination, in an embroidering machine, of a tambour frame, fabric carrying and shifting means mounted therein, and adjustable means actuated by such 100 fabric carrying and shifting means for moving the tambour frame a predetermined distance in a direction reverse to the shift of the fabric.

9. The combination, in an embroidering machine, of a tambour frame, fabric carrying and shifting means mounted therein, and means connected with the tambour frame and optionally connectible and disconnectible from such fabric carrying and 110 shifting means and operable thereby for moving the tambour frame in a direction reverse to the shift of the fabric.

10. The combination, in an embroidering machine, of a tambour frame, fabric shifting rollers carried thereby, tambour 115 frame readjusting means, and manually controlled means for bringing the readjusting means under the operating influence of a shifting roller. 120

11. The combination, in an embroidering machine, of a tambour frame provided with fabric rollers, a gear carried by one of said rollers, tambour frame retracting means embodying a rack, and means for optionally 125 bringing said rack and gear into operative relation.

12. The combination, in an embroidering

machine, of a tambour frame provided with fabric rollers, a gear carried by one of said rollers, tambour frame retracting means embodying a vertically adjustable rack, and means for optionally bringing said rack and gear into operative relation.

5 13. The combination, in an embroidering machine, of a tambour frame provided with

fabric rollers, a gear carried by one of said rollers, tambour frame retracting means embodying a vertically adjustable rack, and means for automatically and optionally bringing said rack and gear into operative relation and for terminating their coöperation.

JOSEPH A. GROEBLI.
